To all whom it may concern:

Be it known that I, FREDERICK S. PINKUS, a citizen of the United States, residing at New York, in the county of New York and State of New York, have invented and produced a new and original Design for Fabrics; and I hereby declare the following to be a full, clear, and exact description of the same.

My invention is a new design for table-cloths and other ornamental fabrics.

The main features of the design consist of ornamental figures of solid color on a background striped with fine lines of different colors.
